(57) **CLAIM**

The ornamental design for a part of a locking device, as shown and described.

DESCRIPTION

1. Part of a locking device

1.1 : Right perspective

1.2 : Left perspective

1.3 : Front

1.4 : Back

1.5 : Right

1.6 : Left

1.7 : Bottom

1.8 : Front perspective

1.9 : Rear perspective

1.10 : Top

The essential characteristics of the design are featured in its shape.

In the reproductions, the broken lines are for the purpose of illustrating portions of the part of a locking device, that form no part of the claimed design.
